UNITED STATES PATENT OFFICE.

ROY H. McELROY, OF DAYTON, OHIO, ASSIGNOR TO INTERNATIONAL CLAY MACHINERY CO., OF DAYTON, OHIO, A CORPORATION OF MAINE.

COMPARTMENT-KILN.

1,264,317.

Specification of Letters Patent. Patented Apr. 30, 1918.

Application filed September 1, 1917. Serial No. 189,400.

To all whom it may concern:

Be it known that Roy H. McELROY, a citizen of the United States, residing at Dayton, in the county of Montgomery and 5 State of Ohio, has invented certain new and useful Improvements in Compartment-Kilns, of which the following is a specification.

This invention relates to new and useful 10 improvements in sectional kilns. One object of the invention is to provide a kiln which permits the pre-heated air from the cooling compartments to be divided and to be delivered to and utilized in burning a 15 plurality of compartments at a time. Another object of the invention is to provide means whereby the waste heat may be conducted either to the main draft flue or a waste heat drier flue. Other objects of the 20 invention will be described in the specification and particularly pointed out in the claims.

Referring to the accompanying drawings, 25 Figure 1 is a longitudinal vertical section on the line 1—1 of Fig. 2. Fig. 2 is a plan view, the upper portion being a section on the line 2^a—2^a and the lower portion being a section on the line 2^b—2^b of Fig. 1. Fig. 3 is a view similar to Fig. 1, same being a 30 section on the line 3—3 of Fig. 4. Fig. 4 is a plan view, the upper portion being a section on the line 4^a—4^a and the lower portion being a view on the line 2^b—2^b of Fig. 3. Fig. 5 is a section on the line 5—5 of 35 Fig. 1. Fig. 6 is a detailed sectional view on the line 6—6 of Fig. 5 showing the method of distributing the gases as they leave the kiln. Fig. 7 is a top plan view of the details shown in Fig. 6.

40 It is to be understood that the present invention may be applied to any well known type of compartment kiln, either single or double battery or *en bloc*.

As is well known, kilns of this type are 45 provided with a plurality of communicating compartments adapted to receive the ware to be burned. The various compartments are progressively fired, and the waste heat from the compartment being fired is conducted to the compartments containing the green ware in front, thereby pre-heating the same, and receiving air to support combustion from the previously fired and cooling compartments in the rear. The green ware 50 is placed in the kiln somewhat in advance

of the compartment being fired and the burnt ware is removed from a compartment somewhat in the rear and after the ware has cooled.

Referring to the kiln as illustrated in the 60 drawings and more particularly to Figs. 1, 2 and 5, 1 represents the kiln which is provided with a plurality of division walls 2 which form the various compartments. The kiln is provided with side walls 3 which 65 form the ends of the compartments and which are provided with door openings 4 adapted to receive wickets 5 and which permits access to be had to the interior of the kiln. The compartments are provided with gas ports 6 which discharge into the compartments behind bag walls 7 located along one side of the compartments. In the present instance the gaseous fuel is supplied to the ports 6 through down-takes 8 which extend through the division walls 2. The down-takes 8 communicate with lateral gas ducts 9 in the present instance located at 70 the top of the kiln. This communication is controlled by valves 10 which control the 75 supply of gas to the ports 6. The down-takes 8 and ducts 9 represent one accepted form of gas distribution, but it will be understood that the gas may be supplied to the compartments by any well known means. 80 The air utilized in supporting the combustion of the fuel enters the compartments through air ports 11 behind the bag walls 7 and below the gas ports 6. The air for the 85 burning compartments is divided and delivered from compartments in the rear, and the gases are conducted away from the burning compartments to the pre-heating compartments in front, through air flues 12 which pass through or beneath the walls 6 90 and under floors 13 of the compartments. The various compartments deliver air or the burnt gases to the flues 12 through perforated portions 14 of the floor. In the construction shown in Fig. 1 it is contemplated 100 that alternate compartments are inter-communicating as are the intermediate compartments, *i. e.*, the first communicates with the third and the second with the fourth. To permit the air and gases to be thus distributed, the flues 12 are of a length equal to twice the width of each compartment and, as will be seen from Fig. 1, extend under two compartments. The floor 13 of the compartments which do not communicate with 105 110

any one flue 12 is solid as at 13, while the floor of any compartment which communicates with any one flue 12 is perforated as at 14. As will be seen from the lower portion of Fig. 2 this arrangement is secured by arranging the flues 12 in a staggered relation, the ends of the flues being formed by the lower portion of the bag walls 7. To permit the end compartments of the kiln to communicate, the kiln, when constructed in a single battery, is provided with a return flue which connects the ends of the flues 12; and when constructed in a double battery or a double row of compartments *en bloc*, lateral return flues are provided, which constructions are not shown but are well known in the art. After the gases have passed through the green ware thereby pre-heating the same, said gases are conducted out of the kiln through lateral draft flues 15 which lie below the various compartments and communicate with the flues 12 below the perforated portions 14 of the floor. The flues 15 extend to the side of the kiln where they may be connected either to a main draft flue 16 or a waste heat drier flue 17. The lateral draft flues 15 are provided with ports 18, while the flues 16 and 17 are provided with ports 19 and 20 respectively. The ports 19 and 20 are located on adjacent sides of each of the ports 18 in a right-angular relation, both being at the same distance therefrom. This arrangement permits the port 18 to be connected with either the port 19 or 20 by a hood 21. When it is desired to utilize the heat of the sulfur gases passing out of the kiln in a waste heat drier, the hood 21 is so placed as to connect any one of the ports 18 with its respective port 20 of the waste heat drier flue 17. When it is desired to conduct the gases to a stack or other draft appliance through the main draft flue 16, the hood 21 is connected with respective port 19 of the main draft flue 16. The main draft flue 16 is provided with any suitable draft appliance such as a fan or stack (not shown). When not in use the ports 18, 19 and 20 may be closed by caps 22.

In Figs. 1 and 2 it is contemplated that a plurality of compartments may be burned by introducing the air into any one of the burning compartments from the next succeeding compartment in the rear, the burnt gases being delivered to the second compartment ahead. In Figs. 3 and 4 the air passing through any two compartments in the rear is divided and delivered to the next two burning compartments ahead. A portion of the air passing through any one cooling compartment is delivered to any one of the burning compartments. This arrangement is secured through the aid of air flues 23 and 24. The flues 23 which are the shorter ones, are of a length approximately

twice the width of the compartments, and said flues deliver half of the air from any one of the cooling compartments to the second compartment ahead. The flues 24, which are the longer ones, are of a length 70 approximately equal to three times the width of the compartments and they deliver the other half of the air from any one cooling compartment to the third compartment ahead. In this instance, the flues are arranged in alternate sets and are in staggered 75 relation, the same as the flues in the first instance, for example, as shown in Figs. 1 and 2. At their left ends the flues 23 and 24 communicate with the compartments 80 from which they receive the air and gases through perforated portions 14 of the floor, and where the flues 23 and 24 pass under compartments with which they do not communicate, the floor 13 thereabove is solid, 85 which construction is similar to that shown in Figs. 1 and 2. The flues 23 and 24 also communicate, in a manner similar to that shown in Figs. 1 and 2, with lateral draft flues 15. The remaining portions of the kiln 90 may be of any accepted and well known construction.

Having described my invention, I claim:

1. In a kiln provided with a plurality of compartments, staggeredly arranged communicating flues connecting said compartments, said flues being each of a length greater than the width of the compartments, whereby a plurality of compartments may be simultaneously burned. 95
2. In a kiln provided with a plurality of compartments, staggeredly arranged communicating flues of a length at least equal to the width of two compartments connecting said compartments, whereby a plurality 100 of compartments may be simultaneously burned. 105
3. In a kiln provided with a plurality of compartments and having a partially perforated floor, communicating flues of a 110 length not less than the width of two compartments connecting alternate compartments, the entering ends of the flues communicating with the compartments through the perforated portions of the floor, whereby 115 a plurality of compartments may be simultaneously burned.
4. In a kiln provided with a plurality of compartments, communicating flues arranged in sets connecting said compartments, said sets being placed in staggered relation whereby a plurality of compartments may be simultaneously burned. 120
5. In a kiln provided with a plurality of compartments, long and short communicating flues arranged in sets connecting said compartments, said flues being arranged alternately and the sets thereof being staggered, whereby a plurality of compartments 125 may be simultaneously burned. 130

6. In a kiln provided with a plurality of compartments, long and short communicating flues connecting said compartments, said flues being arranged alternately, whereby a plurality of compartments may be simultaneously burned.

7. In a kiln provided with a plurality of compartments, long and short communicating flues arranged in sets connecting said compartments, said flues being arranged alternately and the sets thereof being staggered, said kiln having a partially perforated floor through which the compartments communicate with the entering ends of the flues, whereby a plurality of compartments may be simultaneously burned.

8. A kiln provided with a plurality of compartments, air flues connecting said com-

partments, lateral flues connected to said air flues, a main draft flue, a waste heat flue, all 20 of said flues being provided with ports having a right-angular relation, and a hood adapted to connect the port of the lateral flue with either of the ports of the other flues.

9. A kiln provided with a plurality of compartments, air flues connecting said compartments, lateral flues connecting to said air flues, a main draft flue and a waste heat flue, up-takes in right-angular relation 30 for all of said flues, and a hood adapted to connect the lateral flue with either the main or waste-heat flue through said up-takes.

In testimony whereof I affix my signature. 35
ROY H. McELROY.
